SUCTION CLEANER

William N. Patterson, Detroit, Mich., assignor, by
mesne assignments, to The Sparks-Withington
Company, Jackson, Mich., a corporation of
Ohio

Application February 27, 1941, Serial No. 380,753

1 Claim. (Cl. 230—95)

This invention relates to suction cleaners and has particularly to do with that type of suction cleaner which is operated by air under pressure with the use of a jet pump.

An object of the present invention is to provide an improvement on suction cleaners of the type disclosed in Patterson Patent No. 2,183,150, issued December 12, 1939. This patent shows a cleaner with a jet arrangement for creating suction and a device called a vibrator to interrupt periodically the supply of air to the jet pump.

More specifically, it is an object of the present invention to provide an air inlet device for the throat of the cleaner, which device will permit variation in position to comply with sources of air pressure available and to obtain maximum efficiency from each cleaner.

Another object of the invention is to provide a spreading unit for the air jet to accentuate the Venturi effect in the throat of the cleaner.

Other objects and features of the invention, having to do with details of construction and operation, will be brought out in the following description and claim.

In the drawing:

Fig. 1 is a side elevation, partially in section, showing the location of the jet and its relation to the other parts of the cleaner.

Fig. 2 shows the handle portion of the cleaner which would be joined to the head portion of Fig. 1.

Fig. 3 is an enlarged view of a portion of the cleaner head.

Fig. 4 is a sectional view of the jet.

Fig. 5 illustrates a modified jet for different air pressures.

Fig. 6 illustrates the jet and the spreader.

In Fig. 1 the vacuum head is illustrated at 10. It is provided with an entrance nozzle 11, a Venturi throat 12, and a dirt outlet 13. The venturi is formed by a member 14 which is slipped into a bore 15 in the head. A pipe 16 serves as a handle for the vacuum head and also as the means for carrying away the dirt. A raised portion 20 on the head portion includes a valve 21 which is fully described in the above mentioned patent. A flexible tube 22 connects the passages of portion 20 with an air inlet tube 23 which is controlled by a valve 24, details of which have not been shown. The flexible portion 22 is provided to permit movement between head 10 and the lower end 25 of pipe 16. A suitable swivel joint is provided to facilitate the managing of the head on the floor or other surface to be cleaned.

Leading from valve 21 is a passage 30 into which pulsating air will be projected under pressure. The present invention resides in the means for connecting the passage 30 with the Venturi throat 12. This means is shown at 31 and comprises a shaft having an axial bore 32 open at 33 at one end of the shaft, and open at the other

end to radial passage 34 which is spaced between the ends of the shaft. Threaded portions 35 and 36 are provided on the shaft to movably position the same in a threaded bore 37 in the head. These threaded portions seal the bore 37 from the outside of the head but permit the shaft 31 to be available from the outside.

The air pressure which is used with the cleaner depends oftentimes on the source which is available and also, on the type of material which is to be picked up by the cleaner. The length of the shaft 31 and the size of the bore depends on the air pressure to be used and on the quantity of air available. For this reason, shafts of varying lengths and bores are provided, one of these is shown at 31a in Fig. 5. These may be inserted in the same threaded passage 37 and the tip 33 moved back further until it is positioned properly with respect to the venturi 12. The cleaner may be tested with a suitable suction testing mechanism to obtain the proper positioning of the tip 33. It will be noted that the threaded passage is so positioned that the centerline of the shaft coincides with the centerline of the Venturi throat.

In particularly large models, difficulty has been experienced in obtaining a proportionate suction for the amount of air pressure used. This problem has been solved by the provision of an air shaft, as illustrated in Fig. 6. In this shaft, a cone shaped element 40 is positioned, point toward, but spaced from, the open end of the bore in shaft 31. A suitable bracket 41 is used for this purpose. This cone causes an immediate spreading of the air as it leaves the bore and causes a pronounced increase in the Venturi effect. This arrangement also permits a shortening of the throat length and thereby permits large designs without ungainly proportions.

I claim:

40 A device of the character described comprising a cleaning nozzle in the form of an elongated member having a passageway therethrough, said nozzle having a gradually curved bend adjacent one end thereof, said bend resulting in said passageway having one end opening substantially laterally from said member to comprise an entrance nozzle and having the other end comprising a dirt outlet, a Venturi throat in said passageway, said nozzle having an integral head having an integral air inlet passage therein, and a shaft threaded in said nozzle at said bend projecting within and along said passageway toward said Venturi throat, said shaft having an axial bore open at the end towards said throat and closed at the other end, said shaft having lateral passage means between its ends providing communication between said inlet and said bore, said other end of said shaft extending to the outside of said nozzle to present said other end in position to be readily adjusted.

WILLIAM N. PATTERSON.
